UNITED STATES PATENT OFFICE.

WILLIAM M. BRUCE, JR., OF SPRINGFIELD, OHIO, ASSIGNOR TO THE UNITED TELEGRAPH & CABLE COMPANY, OF SPRINGFIELD, OHIO, A CORPORATION OF OHIO.

WIRELESS TRANSLATING DEVICE.

Application filed November 8, 1922. Serial No. 599,714.

My invention relates to improvements in translating devices, particularly adapted for use in wireless reception and it particularly relates to the apparatus referred to in my pending application No. 445,968 filed Feb. 18, 1921.

In the broader aspects of the invention it consists in providing a vibrating receiving device with means for mechanical tuning the same so as to respond to certain definite alternations or oscillations of comparatively low frequency, thus providing for selectivity in receiving signals, particularly of the wireless or so called wired wireless characteristics.

In the accompanying drawings:

Fig. 1 is a plan view of a device embodying my invention.
Fig. 2 is a side elevation of the same.
Fig. 3 is an end or front elevation of the same.

Figs. 4, 5, 6, 7, 8 and 9 are details, particularly of the vibrating contact portions of the same.
The main frame of the device consists preferably of a permanent magnet a of the horse shoe type, the legs of which are provided with pole extensions a^1 and a^2 which extend inwardly to the tuned vibrating coil 30 with which these polar extensions cooperate.

The vibrating coil c is of the usual type of vibrating coil relays. It is of a very light construction and is supported at top and bottom by the suspensions c^1 and c^2 , both of which are preferably provided with adjustable means for varying the tension of the suspensions and thus varying the vibrating period of the coil itself. The upper suspension c^1 consists preferably of two strands of fibrous material, though a metallic suspension may be used. These strands are adapted to be opened and closed by a spreader d which is raised and lowered with an adjusting screw d^1 to vary the tension on the coil by opening or closing the strands of the double suspension. The strands of the upper suspension C' are threaded through a suitable opening in the spreader head d and pass on each side of a depending ear or lug d^2 so that as the spreader head is lowered or raised more or less tension is placed on the strands of the suspension C' . The lower suspension c^2 is preferably connected to a pivoted lever c^3 the opposite end of which is connected to a spring c^4 having an adjust-

ing screw c^5 by which the tension of the spring may be varied. The coil c preferably surrounds a core b^1 projecting outwardly from a supporting head b which supports the coil and which is adapted to slide in ways b^1 and b^3 on the magnet a . Means are provided for holding the head b in different positions of adjustment in the nature of clamping plates b^4 which may be tightened up against the sides of the adjustable head to hold it in proper position of adjustment. The coil mechanism is all mounted upon this adjustable head which can be removed or replaced in the frame as desired. When used as a relay the removable coil is provided with a tongue t which is preferably T-shaped at the end and on opposite sides of the tongue are placed contacts e e with which the tongue engages as it is vibrated with the coil. These contacts are of novel construction and each consists of a sleeve e^1 mounted on the end of an adjustable screw e^2 and in the end of this sleeve is fitted a plate e^3 preferably of silver or some other metal having affinity for mercury. On the face of this plate there is placed mercury as indicated at e^4 in Fig. 7. The sleeve d^1 is made of steel with which the mercury does not unite and it is possible, therefore, to make a mercurial contact by placing the mercury on this plate d^3 which assists very materially in making the proper electrical contact. Where the two contacts e e are employed they are electrically connected together while the tongue itself forms the terminal of the other side of the circuit and as the coil vibrates the circuit is closed by the tongue engaging with the mercury on either or both of the said contacts. The coil c is connected in the usual way so as to be in circuit with the incoming signals and by the supporting means which may be adjusted as to respond only to such vibrations as correspond to its natural period of vibration.

I find it advantageous also to use a flexible tongue and to make the length of this tongue so that its natural period of vibrations will coincide substantially to the natural period of the coil so that the tongue itself is mechanically tuned as well as the coil. The flexible tongue t is preferably supported in a sleeve t^1 in which it may be secured by any suitable means, preferably by a suitable adhesive material in the nature of sealing wax which can be softened by heat and

will harden at ordinary temperatures and adjustment in the length of the tongue can be secured by softening the adhesive material and moving it in or out of the sleeve. 5 I have found by these instruments I can get a range of tuning up to a thousand alternations per second and that the coil and tongue may be made so selective that it will not respond to alternations or vibrations that differ in a small percentage from the one to which it is tuned.

When this instrument is desired to be used as a recorder I substitute for the tongue a siphon which may be also selected as to its 15 length so as to have a natural period of vibration substantially the same as the coil, the ordinary glass siphon being sufficiently flexible to permit it to vibrate in its natural period. I have found with this instrument 20 I can get quite a range of vibration of the tongue when the movement of the coil itself is hardly perceptible. A continuous series of rapid alternations through the coil acts as an impact upon the coil which will 25 vibrate the tongue at the same rate and by reason of its flexibility increase the range at which the coil itself is vibrating.

The usual arrangements are made for establishing electric connections with the 30 tongue and the contacts when used as a relay and in any case with the terminals of the vibrating coil through which the signals are transmitted.

An instrument of this character may be 35 used for wireless reception where signals in radio frequencies are sent out in groups of a certain frequency within the limits of the

mechanical tuning of the instrument. It may be also used in connection with the heterodyne or beat note which may be adjusted to the frequencies to which the instrument is mechanically tuned. 40

Having thus described my invention, I claim:

1. In an electric translating device, a 45 movable coil and means for varying the natural period of vibration of said coil, a flexible tongue on said coil whose length is proportioned to the vibration of the coil so that the period of vibration of the tongue 50 and the period of vibration of the coil are approximately the same.

2. In a translating device such as described, a movable coil having a flexible tongue, means for adjusting the part and tongue to approximately the same natural period of vibration, and a stationary contact for said tongue. 55

3. In a translating device having a movable coil, a flexible tongue connected thereto, 60 a stationary contact adjacent to said flexible tongue, and means for adjusting the period of vibration of said coil in synchronism with the natural period of vibration of said tongue. 65

4. The combination in a relay, with a movable coil, of a flexible tongue on said part, whose length is so proportioned to the vibration of said part that its natural period of vibration is synchronized with the 70 vibrations of said part.

In testimony whereof, I have hereunto set my hand this 6th day of November, 1922.

WILLIAM M. BRUCE, JR.
